Patented Aug. 20, 1974

232,453

GAME DIE

Norman Bialek, 14 Broadview Road,
Westport, Conn. 06880

Filed Mar. 2, 1973, Ser. No. 337,530

Term of patent 14 years

Int. Cl. D21—01
U.S. Cl. D34—5 DT

Fig. 1

Fig. 2 Fig. 3 Fig. 4 Fig. 5

Fig. 6 Fig. 7

FIG. 1 is a perspective view of the game die embodying my new design.

FIG. 2 is a front elevational view of the game die.

FIG. 3 is a left side elevational view of the game die.

FIG. 4 is a rear elevational view of the game die.

FIG. 5 is a right side elevational view of the game die.

FIG. 6 is a top plan view of the game die.

FIG. 7 is a bottom plan view of the game die.

I claim:

The ornamental design for a game die, as shown and described.
